TELECOMMUNICATION SYSTEM

Leslie Baines Haigh and Ladislas Kozma, Antwerp, Belgium, assignors to International Standard Electric Corporation, New York, N. Y.

Application December 20, 1938, Serial No. 246,796
In Belgium December 24, 1937

6 Claims. (Cl. 179—7.1)

This invention relates to telecommunication exchange systems and more particularly to means for determining the charge to be made for a connection.

The object of the invention is to enable the complete charge for a connection on a time and zone basis to be automatically calculated in monetary values.

The invention will be clearly understood from the following description of one embodiment thereof shown in the accompanying drawings in which:

Figs. 1 and 1A when placed side by side show the tariff and time recording circuit associated with a printing register arranged to print the calling and called parties' numbers, the charge for the call, and possibly the basic tariff, time of day, date and any other required data relating to a connection;

Figs. 2, 2A, 3 and 3A show the calculating circuit which is arranged to calculate the charge for a connection from the tariff and time records in the recording circuit, Fig. 1, and transmit the charge to the printing register where it is recorded.

In reading the drawings, Fig. 1A should be placed on the right of Fig. 1. Fig. 2 should be placed above Fig. 2A, Fig. 2A above Fig. 3 and

call. On Figs. 1 and 1A are shown only the connections numbered 1 to 5, which are mentioned in the following description.

The connecting circuit contains two marker switches. The first one, T, receives a series of impulses from the toll translator circuit, which whilst controlling the selection, determines the tariff to be applied to the connection in known manner. This indication of the tariff is maintained by T during conversation. The other marker, M, registers the duration of the connection by advancing one step for each conversational time unit, for example, one minute.

The charge fixing circuit is called for when the connection is released. Once attached, it takes over the tariff indication and determines from the position of the marker M of the connecting circuit the duration of the conversation. By means of these two indications, a translator finder is placed in the corresponding position, in which is indicated the total charge to be paid by the subscriber. This charge is sent in the form of monetary figures to the printing register, and when this has been done, both the connecting and charge fixing circuits release.

Both circuits under consideration have been based on the present Belgian tariff law, which is as follows:

Distance in Km.	First 3 min.		Second 3 minutes						Following minutes	
	Day	Night	4th min.		5th min.		6th min.			
			Day	Night	Day	Night	Day	Night	Day	Night
10-20.....	0.80	0.80					0.80 per 3 min.		Per 3 min.	
20-30.....	1.20	1.20					1.20 per 3 min.		Do.	
30-40.....	2.00	2.00					2.00 per 3 min.		Do.	
40-50.....	3.50	2.50					3.50 fr. per 3 min. (day)		Do.	
							2.50 fr. per 3 min. (night)			
50-75.....	5.00	4.00	2.00	2.00	1.50	1.00	1.50	1.00	1.50	1.00
75.....	6.00	5.00	2.00	2.00	2.00	1.50	2.00	1.50	2.00	1.50

Fig. 3 above Fig. 3A. Figs. 2 and 2A should be placed on the right of Fig. 1A.

The purpose of these two circuits is first to determine the charge for a telephone communication from two factors, which are the unit tariff and the conversation time, and then to send this charge, in the form of digits representing the monetary value, to the printing register, in which a ticket already shows other particulars of the connection.

General operation

The printing register connecting circuit is permanently associated with a printing register, which is partially shown at the left hand side of Fig. 1A. The connecting circuit may be directly connected to a junction circuit, or can be attached over a finder whenever printing is required for a

45 Connections within the 10 km. zone are considered as local connections and are charged directly on the service meter, and no ticket is produced.

50 It is evident that the size of the markers and finders employed imposes certain limits as regards the duration of conversation. The circuits under consideration are prepared for a maximum conversation time of 42 minutes, but this time can be easily lengthened if required, by means of additional material. A connection lasting more than 55 42 minutes is broken down.

Circuit description

During selection, the digits of the called subscriber's number are sent from the junction circuit over wire 1 to the digit printer (not shown)

contained in printing register PR, and each time a complete digit is sent in, a printing indication is passed to the printing register via wire 2, which causes the recorded digit to be printed and DP to be returned to normal. When selection is completed, the calling subscriber's number and, if required, the fundamental tariff i. e. the charge per time-unit of conversation, are printed in the normal way. The tariff is also recorded via wire 5 on switch T which takes up one of eight tariff positions.

The conversation time measurement must have an accuracy of two seconds, and must be started at the moment the called subscriber answers.

The answer of the subscriber is signalled by the operation of relay S from the junction circuit over wire 4. S connects ground to a contact TSC which may be called the "two-seconds" contact, which is a contact on a common relay energised every two seconds from a clock contact. The two-second impulses are reduced by a set of three relays A, B and C to impulses of six seconds. The first earth pulse via s2, 2 second contact, b1, c1, A operates relay A, which locks via right hand winding of B, a1, s2. Relay B operates. The second pulse via 2 second contacts, b1 left hand windings of B and C. C operates and locks via its right hand winding, c2, winding of A, c3, a1, s2. B releases, its right hand winding being short circuited. The third pulse via b1, c1, short circuits A, which releases, and holds C via c1, c2. Earth is now connected via a2, c4, until C releases at the end of the third pulse.

Since the identification of the calling subscriber takes place after selection, the called subscriber will normally answer before identification is completed. Therefore, the digit printer DP is not available for counting the first minute. Arrangements have therefore been made to count the first minute by the minute marker MM. The earth pulses via a2, c4 pass via n1 to magnet MM. At the first step of MM, relay E operates via s4, ma and locks via e3. When after one minute, MM reaches the tenth terminal, relay N operates via mc and locks via n2, e4. Via o3 back and n4 closed, MM is driven to terminal 1, at which relay O operates via n3, mc, and locks via n3, o3. At the next six-second impulse, MM makes one step (MM, c5, a3, dpa) and DP starts to advance by the 6-second impulses, DPM, n1, c4, a1.

The step taken by MM is to register the second minute now being counted by DP. The next nine pulses step DP only. On arriving on contact 10 after one minute 54 seconds of conversation, DP automatically homes; DPM and its interrupter dpa.

The next pulse, the first of the third minute, steps MM and DP as before. The third minute is then registered on MM which steps to position 3. DP counts each minute in turn and MM records each minute at its commencement. On reaching its last contacts, MM has recorded twenty-one minutes.

At the beginning of the twenty-second minute, MM steps to normal in which position T operates via o1, winding of S, s5, ma, and locks via t2, e4. A circuit is also completed for MM via its interrupter n4, o4, s3, mc, and M steps to position 1 to record the twenty-second minute. The energization of T records that M has made a complete revolution.

Forty-two minutes is the maximum length of call allowed and when M reaches its last contacts a second time at the beginning of the forty second minute, earth via mc, t3 energises R. At the

end of the minute earth via dpa, a3, c5, r1 is connected to the breakdown lead BDL.

When the subscriber hangs up, or breakdown occurs, relay S is released, and test potential is connected via o2, s6, e2 to the arc of the connecting finders CF of the charge fixing circuits, Figs. 2, 2A, 3 and 3A, and at the same time their starting relays Fs, St are energised.

If the subscriber releases during the first minute, N operates via s1, e4, and M is driven to position 1, corresponding to one minute conversation over MM and interrupter, n4 and o3. In position 1, O operates and opens the drive of M.

It may be mentioned that the first six seconds conversation time is free of charge, since E has not been energised, and if the subscriber releases before this time has elapsed, the connecting circuit releases immediately and no sum is printed on the ticket MM and interrupter e1, s4, ma. The charge fixing circuit is called for only if relay Er is already operated.

The connecting finder CF of the charge fixing circuit is stopped by the operation of the test relay Ft; earth fa, cn6, da, ha, ga, Ft, cfg, lead g, Fig. 1A, e2, s6, o2, test potential. After successful double test, Dt and Cn energise in known manner. Relay Js energises via ed3, cn5, pn3, db and in turn operates Bd via ed2, ss2, pn1, cn6, fa. The interrupter DI is now connected to relay Is. Relay Bd can only operate during the opening period of DI, and thus Is always receives full impulses. Relay Bd locks via ed2, bd3. The impulses of Is are sent simultaneously to switch magnet MM, Fig. 1A via mb, Fig. 1A lead d, c/d, Fig. 2A, is1 and to HM of the charge fixing circuit via ti2, tr3, is2. When switch MM, Fig. 1A arrives at its normal position, relay Ti operates via tr2, cn3, c/c, lead c, Fig. 1A, ta off normal, ma to earth. The impulses are now sent to the magnets TM and GM, respectively. These impulses stop when TM reaches its normal position, at which moment Ti releases. In this way, switch H, Fig. 2 is set to a position which is complementary to that of M, Figs. 1 and 1A and G, Fig. 2A is similarly set to that of T, Fig. 1A.

When Ti operated, it energised Th, via ti1, dt1. Th locks in series with Tr when Ti releases after the setting of G. Tr causes the rotation of the 100-point translator finder TF. The arc of TF is subdivided into sectors, each corresponding to one tariff unit. For the Belgian tariff scheme, 8 positions on TM, and therefore 8 sectors on TF, are required (0.80, 1.20, 2.00, 2.50, 3.50, 4.00, 5.00, 6.00 fr.). Five of these tariffs are charged in three-minute units, and therefore TF must have 14 positions for maximum 42 minutes conversation time. These 14 positions are arranged in two levels of 7 positions each, whereby the changing-over from the first level to the second is effected by relay Sh, which operates if relay T in the connecting circuit has been energised, i. e. if the conversation time is more than 21 minutes; Sh, cfa, lead a, Fig. 1A, t1 Fig. 1. For the last three tariffs, one position is reserved for each minute, which means 21 positions in two levels.

For the eight different tariffs, therefore, $5 \times 7 + 3 \times 21$, or 98 positions on TF are required.

Switch G records the tariff of which there are eight variants. Eight contacts of wiper gc are therefore respectively multiplied to groups of seven and twenty-one contacts in the bank tfa according as the tariff is to be charged on a three-minute basis or a minute basis. Wiper tfa is connected to wiper t/b, the individual contacts of the seven-contact groups in bank t/b are

cross-connected to corresponding groups of three contacts in bank *hb* of the time-recording switch *H*. In a similar way, the individual contacts of the "twenty-one contact" groups in bank *tfb* are cross-connected to individual contacts in bank *hc* of the time-recording switch.

The magnet *TFM* of switch *TF* is energized via *tt2* back, *to4* operated. *TF* is stopped by the operation of *Tt* via *gb*, *hb* or *hc* according to the type of tariff, *tfb*, *tfa*, *gc*, earth. The set position of *TF* is therefore individual to the particular combination of tariff and call duration recorded on *G* and *H*.

When relay *Ti* released and *Tr* operated, *Is* still continued to send impulses via *is1*, *ifd*, lead *d*, Fig. 1, *mb* and *tb* both in normal position to *DPM*. Contacts *tr3* have disconnected contacts *is2* from magnets *HM*, *GM*. These impulses have to reset *DP* to its normal position. When this is reached, relay *Pn* operates via *tr1*, *cfb*, lead *b*, Fig. 1A, *dpa*, Fig. 1. Contacts *pn3* release *Js* which releases *Bd*, and the impulses stop. The marker *DM* leaves its normal position and stops on terminal *L*, *DM*, and its interrupter, *pn3*, *db*.

When the translator finder is set (*Tt* operated) and the digit printer is in normal (*Pn* operated), relay *Ss* operates via *tt1*, *pn2*, and the sending of the figures of the total charge can be started.

Earth via *ss5*, *ed3*, energizes *Js*, which closes the operating circuit of *Bd*; battery *js2*, *Bd*, *ed2*, *ss2*, *pn1*, *cn6*, *fa*, earth. At the first opening of the interrupter, *Bd* operates and *Is* starts to produce dial impulses. These are sent simultaneously to the digit printer and to the control marker switch *F*.

As the maximum charge for 42 minutes conversation is 84.00 fr., four figures have to be produced, of which the last is always "0." The first figure is replaced by a dash if the sum to be paid is less than 10 francs. In addition, the francs and centimes are separated by a dash, which is produced in the third position of *DM*. Thus five printing indications are sent to the printer in positions 1, 2, 3, 4 and 5.

The contacts of bank *fb* are cross-connected according to the digits of the charge to be made to the different contacts in banks *tfc*—*tfh*.

Wipers and banks *tfc*, *tfd*, *tfe* determine three digital values for each of ninety-eight different charges, and *tf*, *tfg*, *tfh* for each of another ninety-eight charges.

When impulses corresponding to the first digit have been sent to *DPM* Fig. 1 via *is1*, and from *is2* via *tr3* operated, *ss4* operated, *bd2* operated, relay *Ed* is energized via *ss1*, *fb*, *tfc* or *tf* according as *Sh* is not or is operated, contact *1* and wiper *db* to earth. *Ed* releases *Bd* and *Js* and *Bd* in turn disconnects *DI* from *Is* so that impulsing ceases.

Pn was of course released when *DP*, Fig. 1, stepped off-normal. Contacts *ed1* operate *DM*. Earth via *ed5*, *tr2*, *cn3*, *cfc*, lead *c*, Fig. 1A, *ta*, operates printer magnet *PM* to print the digit recorded by *DP*, and automatically to home the digit recorder *DP*.

Switch *F* is homed; *FM*, *bd2*, interrupter of *FM*, *fa*, earth. *Ed* is released at *fb* and switch *DM* steps to position 2.

If the charge was less than ten francs, *Ed* would have operated immediately *Ss* energized; *Ed*, *ss1*, *fb* in normal position, *tfc* or *tf*, *sh1*, *db*.

The printer would have received a printing impulse in normal position and would have

printed a dash. Release of *Ed* allows *Js* to re-operate via *ed3*, *ss5*, and *Bd* then energises via *ed2*, *ss2*, *pn1*, *cn6*, *fa*. Impulsing recommences via *is1* to *DPM*, Fig. 1, and via *is2*, *tr3*, *ss4*, *bd2* to *FM*.

When *F* is set to the value of the units digit of the charge, *Ed* reoperates via *fb*, *tfd* or *tfg*, *sh2*, contact 2 and wiper *db*.

Again the digit set up on *DP* is printed and 10 *DP* is homed. In addition *F* is homed as before and *D* is stepped to position 3. A dash is then printed due to direct cross-connection between the normal contact of *fb* and contact 3 of *db*. *D* is stepped to position 4 and the third digit, 15 the first decimal digit, is then set up on *DP* under control of *tfe* or *tfh* and printed.

The fourth digit is transmitted in the same way but under control of the direct marking connection between contact 0 of *fb* and contact 20 5 of *db* since in this embodiment the second decimal figure is always 0.

Switch *D* is now stepped to position 6, and earth via *db*, *th4*, *cfe* and lead *e*, Fig. 1A, short circuits relay *E* which releases, followed by *T*, 25 *Fig. 1A* as well as by *N*, *O*, *R*, Fig. 1, and by *Ft*, *Dt*, *Cn*, *Tr*, *Th*, *Ss*. *F* homes; *FM*, *bd2*, interrupter, *fa*. *D* now homes; *DM*, interrupter, *da*, *cn6*, *fa*. *H* then homes; *HM*, interrupter, *ha*, *da*, *fa*; and lastly *G* homes; *GM*, interrupter, *ga*, *ha*, *da*, *fa*, and all the circuits are back at normal.

What is claimed is:

- Fee determining equipment for telecommunication exchange systems comprising a number of tariff-recording terminals, switching means responsive to the establishment of a telecommunication connection for making contact with one of said tariff-recording terminals in accordance with the tariff schedule applicable to such telecommunication connection, a number of duration-recording terminals, switching means responsive to the continuance of an established telecommunication connection for making contact with one of said duration-recording terminals in accordance with the duration of the telecommunication connection, said fee determining equipment comprising a large number of groups of terminals each such group of terminals 35 representing a different combination of tariff schedule and call duration, means for making contact with one of said groups of terminals under the joint control of said tariff-recording and call-duration contacts, means for indicating a series of separate digits representing the several digits of the total fee for a telecommunication connection and connections from one individual contact of said group of contacts for controlling the indication by said means of one of said digits and connections from another individual contact of said group of contacts for controlling the indication thereby of another of said digits.
- Fee determining equipment as claimed in claim 1, including a switching mechanism containing a plurality of rows of terminals and wiper brushes for simultaneously passing over said rows of terminals so as to at any time make contact with one terminal in each of said rows; and wherein one of said rows of terminals comprises said tariff-recording terminals, another of said rows of terminals comprises said duration-recording terminals, and a number of other rows of terminals comprise said large number of groups of terminals, each such group of ter-

minals having one terminal in each row of said number of rows.

3. Fee determining equipment according to claim 1, wherein said groups of terminals include for a first tariff schedule a certain number of groups corresponding to call durations differing by time steps of a certain fineness and for a second tariff schedule a larger number of groups of terminals corresponding to call durations differing by time steps of greater fineness, and wherein said duration-recording terminals include a first set of duration-recording terminals containing a certain number of electrically separate terminals corresponding to call durations differing by time steps of said certain fineness and a second larger set of duration recording terminals corresponding to call durations differing by time steps of said greater fineness, whereby calls made under said first and second tariff schedules are charged for on different time bases.

4. Fee determining equipment as claimed in claim 1, including a switching mechanism containing a plurality of rows of terminals and wiper brushes for simultaneously passing over said rows of terminals so as to at any time make contact with one terminal in each of said rows; wherein one of said rows of terminals comprises said tariff-recording terminals, another of said rows of terminals comprises said duration-recording terminals, and a number of other rows of terminals comprise said large number of groups of terminals, each such group of terminals having one terminal in each row of said number of rows; and wherein said means for making contact with one of said groups of terminals under the joint control of said tariff-recording and call-duration contacts comprises connections for establishing a marking circuit through that one of said duration-recording terminals and that one of said tariff-recording terminals which are passed over by said wiper brushes simultaneously with each other and with the terminals of said one of said groups.

5. In a telecommunication exchange system of the type comprising a number of tariff recording terminals, switching means responsive to the establishment of a telecommunication connection for making contact with one of said tariff-recording terminals in accordance with the tariff schedule applicable to such telecommunication connection, a number of duration-recording

terminals, switching means responsive to the continuance of an established telecommunication connection for making contact with one of said duration-recording terminals in accordance with the duration of the telecommunication connection, a calculating device comprising a large number of groups of terminals each such group of terminals representing a different combination of tariff schedule and call duration, including means for making contact with one of said groups of terminals under the joint control of said tariff-recording and call-duration contacts, means for indicating a series of separate digits representing the several digits of the total fee for a telecommunication connection, and connections from one individual contact of said group of contacts for controlling the indication by said means of one of said digits and connections from another individual contact of said group of contacts for controlling the indication thereby of another of said digits.

6. A telecommunication exchange system comprising a number of tariff-recording terminals, switching means responsive to the establishment of a telecommunication connection for making contact with one of said tariff-recording terminals in accordance with the tariff schedule applicable to such telecommunication connection, a number of duration-recording terminals, switching means responsive to the continuance of an established telecommunication connection for making contact with one of said duration-recording terminals in accordance with the duration of the telecommunication connection, characterized by the provision of a calculating device comprising a large number of groups of terminals each such group of terminals representing a different combination of tariff schedule and call duration, means for making contact with one of said groups of terminals under the joint control of said tariff-recording and call-duration contacts, means for indicating a series of separate digits representing the several digits of the total fee for a telecommunication connection, and connections from one individual contact of said group of contacts for controlling the indication by said means of one of said digits and connections from another individual contact of said group of contacts for controlling the indication thereby of another of said digits.
